UNITED STATES PATENT OFFICE.

HORACE W. KING, OF ANN ARBOR, MICHIGAN, ASSIGNOR TO KING-SEELEY CORPORATION, OF ANN ARBOR, MICHIGAN, A CORPORATION OF MICHIGAN.

LIQUID-DEPTH-INDICATING DEVICE.

Application filed April 1, 1920. Serial No. 370,418.

The invention relates to devices for indicating the depths of liquids and refers particularly to that type of device in which air under pressure displaces the liquid from an air chamber communicating with the body of the liquid at the full depth to be measured. The pressure of this air is equal to the hydrostatic head of the liquid down to its point of communication with the air chamber, so that a pressure gage to which the pressure of the air is transferred can indicate by suitable graduations, the depth or the amount of the liquid. The invention is particularly applicable for indicating the depth or amount of liquid fuel, such as gasoline, in automobile fuel tanks. One object of the invention, is the provision of means for heating inclosed air to expand the same, thereby producing a pressure sufficient to displace any liquid fuel from the air chamber down to its point of communication with the body of the liquid fuel. Another object is the provision of means for automatically supplying air to take the place of any of that which escapes from the air chamber and passes up through the liquid fuel. Further objects of the invention reside in the novel arrangements and combination of parts as more fully hereinafter set forth.

In the drawings the figure is a diagrammatic view partly in section of a construction embodying my invention:

1 is an automobile fuel tank containing liquid fuel, such as gasoline. 2 is a suitable air chamber preferably of cylindrical form within the tank and adjacent to its bottom, this air chamber being provided with a suitable aperture 3 in its side wall and near its bottom to place the interior of the air chamber in communication with the liquid fuel. 4 is a substantially vertical tube having its lower end open and terminating inside the air chamber 2 at substantially the same level as the opening 3. 5 is a second substantially vertical tube preferably of larger diameter than the tube 4 and having its lower end open and communicating with the interior of the air chamber near the top thereof. This lower end is preferably beveled so that when air is being forced through the tube 4 into the air chamber 2 to displace the liquid

fuel therefrom, the liquid in the tube 5 will more readily flow therefrom and be displaced by the air.

The upper ends of the tubes 4 and 5 are connected to the cover or cap 6, which is removably mounted upon the top of the tank 1. As shown, 7 is a cylindrical flanged securing member permanently secured upon the top of the tank 1, and 8 is a nut threadedly engaging the cylindrical flanged member and clamping the cover or cap therebetween, there being preferably a washer 9 between the cover or cap and the outer end of the cylindrical flanged member.

10 and 11 are nipples secured to the outer side of the cover or cap 6 and having apertures 10' and 11' respectively communicating with the tubes 4 and 5, respectively. 12 is a pipe having one end secured to and communicating with the aperture 11' of the nipple 11 and the other end secured to and communicating with a leg of a suitable pressure gage 13, such as a U-tube.

For the purpose of creating sufficient pressure of air in the tube 4 to displace the liquid fuel from the air chamber 2 and tube 5, I have provided the following construction: 14 is a closed air tank secured against the exhaust manifold 15 of an internal combustion engine. 16 is piping connected to and communicating with the nipples 10 and 17, this latter nipple being secured to the closed tank 14 and communicating therewith.

As thus far described, in operation, upon starting the internal combustion engine, the exhaust manifold 15 will become heated, which in turn heats the closed tank 14 and the air enclosed therewith. The heating of this air increases the pressure thereof and consequently increases the pressure of the air in the piping 16 and tube 4, so that the liquid fuel within the air chamber 2 and within the tube 5 will be displaced therefrom and forced through the aperture 3 in the air chamber into the body of the liquid fuel. The pressure of the air in the air chamber counterbalances the hydrostatic pressure exerted by the liquid fuel within the tank 1 above the aperture 3 and the pressure gage 13 having one leg in communication with the air chamber by means of the tube 5 and

pipe 12, indicates the depth or quantity of the liquid fuel in the tank 1 and above the aperture 3.

One disadvantage of this system, is that some of the air escapes through the aperture 3 and up through the liquid fuel, thereby becoming lost. As a consequence when the engine is stopped and the closed air tank 14 and piping 16 resume their original temperatures, the amount of air therewithin will not be the same as originally, thereby preventing the device from operating after it has been once heated. For the purpose of maintaining approximately the same amounts of air in the system as the amount originally contained and when the system is at original temperature, the closed vertical container 18 is provided in the piping 16. In detail, this piping comprises the pipes 19 and 20, respectively connected to the nipples 10 and 17 and the nipples 21 upon opposite sides of the container 18 near its top. 22 is a tube having an open upper end communicating with the air outside the container 18 and extending longitudinally within the same. The lower end is open and terminates adjacent to the bottom of the container. 23 is a suitable sealing liquid, such as mercury, at the bottom of the container 30 and surrounding the lower end of the tube 22.

In operation when the motor is running the exhaust manifold 15 is heated and in turn heats the closed air tank 14 thereby expanding the air in the tank and causing a portion of the air to pass through the pipe 20, across the top of the container 18, through pipe 19, tube 4 and into the air chamber 2. This air escapes from the lower end of the tube 4, displaces the liquid fuel in the air chamber and tube 5 and a portion escapes through the aperture 3 in the air chamber. When the air is being expelled the pressure in the closed tank 14, pipe 20, container 18, pipe 19, tube 4, and air chamber 2 is the pressure due to the depth of the liquid fuel in the tank 1 plus atmospheric pressure, there being an aperture 24 in the top of the tank 1. The sealing liquid 23 in the container 18 rises in the tube 22 a depth sufficient to balance this pressure. The tube 5 and pipe 12 convey the pressure in the air chamber 2 to the pressure gage 13 which indicates the depth of the liquid fuel in the tank. When the pressure on the top of the liquid fuel in the tank is atmospheric, it is not necessary to have a tube leading from the top of the tank to the other leg of the pressure gage.

When the engine stops running the exhaust manifold 15 and air tank 14 are cooled, air then returns to the air tank, this air being supplied through the tube 22, bubbling up through the sealing liquid 23 in the container 18 and passing through the pipe 20. 65 While air is returning to the air tank 14,

liquid fuel enters through the aperture 3 into the air chamber 2 and eventually seals the lower end of the tube 4. This liquid fuel will rise in the tube 4 to an elevation above the elevation of the liquid fuel in the tank, 1, depending upon the partial vacuum in the system, and balances the pressure of a column of the sealing liquid having a height equal to the difference in level between the surface of the sealing liquid 23 and the bottom of the tube 22. The nipples 21 mounted on the container 18 are located at a sufficiently high elevation to prevent the entrance of the liquid fuel through the tube 4 and pipe 19 when the air tank 14 is re-cooling.

From the above description it will be readily seen that I have provided a device for indicating the depth or amount of a liquid in which the pressure of the displacing air is raised by a member having a function other than that of giving off heat. Furthermore I have provided means for supplying air to the system, when the latter re-cools, to replace the air escaping from the system. Also, by having the tube for conveying the air under pressure terminating at substantially the level of the point of communication of the air chamber with the liquid and the pressure gage connected into the top of the air chamber, the gage will give the correct reading regardless of whether the engine is running or at rest.

In general, it may be stated that my device provides for automatically clearing air chamber 2 of liquid fuel whenever the motor starts and stops and at the same time automatically corrects the reading of the gage. From experience I have found that such correction is necessary every few days.

What I claim as my invention is:

1. The combination with an air chamber communicating with a liquid at the full depth to be measured, of an air conduit communicating with said air chamber at one end and extending therefrom outside the liquid but being closed to the atmosphere under normal working conditions, means for heating the air in said conduit to expand the same and cause displacement of the liquid in said air chamber down to its point of communication with the liquid, a pressure gage, and means for transmitting the pressure of the air in said air chamber to said pressure gage.

2. The combination with an air chamber communicating with a liquid at the full depth to be measured, of a member adapted to supply heat, a hollow air vessel communicating at one point with said air chamber and extending thence adjacent to said heat supplying member, whereby the air in the vessel is heated and expanded to displace the liquid in said air chamber down to its point of communication with the liquid, a

- pressure gage, means for transmitting the pressure of the air in said air chamber to said gage, and means for replacing in the air confining system including said chamber, 5 vessel and pressure transmitting means any air escaping therefrom by said air chamber, said means operating when said hollow air vessel resumes its original temperature.
3. The combination with an air chamber 10 in a liquid and communicating therewith at the full depth to be measured, of a tube communicating with said air chamber, a closed air tank communicating with said tube, means for heating said closed air tank, a 15 closed container in the communication between said tank and tube, a tube communicating with the air outside said container and extending thereinto, means for sealing the inner end of said tube during the time 20 the air in said tank is at a temperature above the original temperature, said means permitting of the inward flow of the air from outside said container to replace any air escaping from said air chamber, when the air 25 in said tank recools to its original temperature, and a pressure indicator communicating with said air chamber.
4. The combination with a tank containing liquid fuel, of an exhaust manifold, an 30 air chamber in said tank communicating with the liquid fuel therein at the full depth to be measured, a vertical tube having its lower end opening into said air chamber at substantially the level of the point of communication of said air chamber with the 35 liquid fuel, a closed air tank adjacent to said exhaust manifold, a closed container, pipes leading from said tube and closed air tank to said container, a vertical tube extending 40 within said container and having its upper end open to the air outside said container and its lower end open and terminating adjacent to the bottom of said container, a sealing liquid within said container and surrounding the lower end of said tube there- 45 within, and a pressure gage communicating with said air chamber near the upper end of the latter.
5. In an apparatus of the class described, 50 the combination of a liquid container, pressure responsive means for indicating the depth of liquid therein, a pressure transmitting conduit extending from said means to the container and provided with an opening whereby liquid from the container may enter it at a point below level of liquid in 55 said container and temperature responsive means for introducing air into said conduit.
6. In an apparatus of the class described, 60 the combination of a liquid container, pressure responsive means for indicating the depth of liquid therein, a pressure transmitting conduit extending from said means to the container and provided with an open- 65
- ing whereby liquid from the container may enter it at a point below level of liquid in said container, said conduit being also enlarged at its liquid receiving end, and temperature responsive means for supplying air to said enlarged portion to lower the level of liquid therein.
7. In an apparatus of the class described, 70 the combination of a liquid container, pressure responsive means for indicating the depth of liquid therein, a pressure transmitting conduit extending from said means to the container and provided with an opening whereby liquid from the container may enter it at a point below level of liquid in 75 said container, and means forming an air confining chamber connected with said conduit at a point below a level of liquid therein, whereby expansion of air in said chamber will cause a portion of said air to be discharged into the conduit.
8. In an apparatus of the class described, 80 the combination of a liquid container, pressure responsive means for indicating the depth of liquid therein, a pressure transmitting conduit extending from said means to the container and provided with an opening whereby liquid from the container may enter it at a point below level of liquid in 85 said container, and means forming an air confining chamber connected with said conduit at a point below a level of liquid therein, whereby expansion of air in said chamber will cause a portion of said air to be discharged into the conduit.
9. In an apparatus of the class described, 90 the combination of a liquid container, pressure responsive means for indicating the depth of liquid therein, a pressure transmitting conduit extending from said means to the container and provided with an opening whereby liquid from the container may enter it at a point below level of liquid in 95 said container, and means forming an air confining chamber connected with said conduit at a point below a level of liquid therein, whereby expansion of air in said chamber will cause a portion of said air to be discharged into the conduit, and means permitting entrance of air to said chamber.
10. The combination with a motor vehicle fuel tank containing liquid fuel, said tank being normally open to atmospheric pressure and having a closable enlarged 105 opening in the upper wall thereof, of an enlarged air chamber insertable downwardly in the said tank through said enlarged opening and extending into the liquid fuel and positioned near the bottom of said tank, said 110 air chamber having a closed upper wall and an opening below said upper wall for placing the interior of said chamber in communication with the liquid fuel in said tank, a pressure transmitting tube communicating 115

with the upper portion of said air chamber, a pressure gauge connected to and communicating with the interior of said pressure transmitting tube, means for replenishing the air in said air chamber including a second tube extending from above the normal surface of the liquid fuel and having its lower end opening directly into the air chamber, a cover for closing the enlarged

opening in the tank through which said chamber is inserted, said cover being supported upon said tank and carrying said tubes and chamber as a unit, and means for producing flow of air through said second tube directly into said air chamber.

15

In testimony whereof I affix my signature.

HORACE W. KING.
